W. E. WEEKS

ADJUSTABLE CHAIN LINK

Filed Feb. 14, 1925

FIG. 1

FIG. 2

William E. Weeks
INVENTOR

by J. M. Thomas
Attorney

UNITED STATES PATENT OFFICE.

WILLIAM E. WEEKS, OF SALT LAKE CITY, UTAH.

ADJUSTABLE CHAIN LINK.

Application filed February 14, 1925. Serial No. 9,108.

To all whom it may concern:

Be it known that I, WILLIAM E. WEEKS, a citizen of the United States, residing at Salt Lake City, in the county of Salt Lake 5 and State of Utah, have invented certain new and useful Improvements in an Adjustable Chain Link, of which the following is a specification.

My invention relates to chains and has 10 for its object to provide a new and efficient means of shortening and tightening chains when desired in fastening anything therewith and when the links are too long to make the desired adjustment by omitting a 15 link.

A further object is to provide an adjusting means where one or more links are used.

These objects I accomplish with the de- 20 vice illustrated in the accompanying drawings in which similar letters and numerals of reference indicate like parts throughout the several views and as described in the specification and pointed out in the append- 25 ed claim.

In the drawings, of which I have shown the best and most substantial embodiment 30 of my invention, Figure 1 is a plan view of the device with the links shown drawn together as the chain is shortened, and Figure 2 is a side elevation of the device showing the chain links in the extended position and dotted lines showing the links in the contracted position.

35 A metal plate A is provided having a serrated edge 1 for easier turning by hand

when the device is small. Semicircular slots 2 and 3 are cut in the plate A, and which are offset from the axis of the said plate A, with their axes on the diametrical line 40 of said plate, and having their axes equidistant from the axis of the said plate. Each of said slots being involute as to the axis of the said plate A. Small semi-circular notches 4, 5, 6, and 7, are cut in 45 the outside edges of the respective slots 2 and 3 for use when short adjustments are desired and the full adjustment is not required. The stress on the ends of the chain will keep the links 8 and 9 in the respective 50 notches in which they are placed.

When the device is made on a large scale a wrench may be used to turn the plate A to the desired notch for shortening the chain or cable used.

55 This device may be used in tightening cables, ropes and wires as well as chains and could be used to tighten the wires on an air plane after they have become stretched from long use.

Having thus described my invention I desire to secure by Letters Patent and claim:—

60 A device of the class described comprising a circular plate having two semi-circular slots cut therein; notches in the outside edges of said slots; and links of a chain engaged with said plate through said slots.

65 In testimony whereof I have affixed my signature.

WILLIAM E. WEEKS.
